UNITED STATES PATENT OFFICE

2,437,340

SUCTION DEVICE FOR REMOVING DUST
FROM FABRIC OR THE LIKE

Alfred J. Zugehoer, Hamilton, Ohio

Application December 1, 1944, Serial No. 566,207

1 Claim. (Cl. 15—15)

1

The present invention relates to new and useful improvements in devices for cleaning dust rags and other cloth articles by suction means adapted to draw loose dirt and the like from the articles and the invention has for its primary object to provide a receptacle within which the article may be placed and subjecting the article when in the receptacle to the action of a suction device for drawing dust, dirt and other loose particles from the article.

An important object of the present invention is to provide a cleaning device of this character equipped with a motor driven fan to produce the desired suction, or which may be attached to a conventional form of vacuum cleaner for supplying the necessary suction within the container.

A further object of the invention is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a vertical sectional view taken substantially on a line 1—1 of Fig. 2, and

Figure 2 is a transverse sectional view taken substantially on a line 2—2 of Figure 1.

Referring now to the drawings in detail wherein for the purpose of illustration I have disclosed a preferred embodiment of the invention, the numeral 5 designates a base having an annular fan housing 6 secured thereto, the fan housing having an electric motor 7 attached to its bottom wall and to which a suction fan 8 is operatively attached and positioned in the housing 6.

The top wall of the fan housing is formed with a central opening 9 and secured to the top of the fan housing is a container 10 including a continuous outer wall 11 and a continuous inner wall 12 integrally connected at their upper edges.

The top of the container is open and the inner wall 12 is spaced from the outer wall 11 and the inner surface of the inner wall 12 is formed with shallow recesses 13 having openings 14 formed therein. The inner wall 12 and the recesses 13 arranged about the inner surface of said wall form a basket-like receptacle for the reception of a dust-containing-fabric therein.

A neck 15 is formed at one side of the fan housing 6 and extends substantially tangentially therefrom and to which a dust collecting bag 16 may be attached.

Upon the operation of the motor 7 a suction

2

force will be created by the fan 8 to draw air from the container 10 through the opening 9 and into the bag 16. Accordingly, by placing a dust cloth or other cloth article or garment 17 within the basket-like receptacle the suction force thus created by the fan 8 will draw dust, dirt and other loose particles from the article 17 through the openings 14 and thus discharge the same into the bag 16.

10 If desired, the motor 7 and fan 8 may be eliminated and a suction hose of a conventional form of vacuum cleaner (not shown) may be attached to the neck 15 to create the necessary suction in the container 10.

15 It is believed that the details of construction and manner of use of the device will be readily understood from the foregoing without further detailed explanation.

Having thus described the invention, what I claim is:

20 In a device for removing dust from fabric and the like, a base, a housing provided with an opening in its top wall thereof mounted upon said base, a fan mounted for rotation in said housing, 25 a container having an open bottom mounted upon the top wall of said housing and secured to the latter, the open bottom of said container being in communication with the opening in the top wall of said housing, said container embodying 30 a continuous outer wall and a continuous inner wall arranged within said outer wall and spaced from the latter, the inner wall being provided with cup-shaped recesses arranged about the inner surface thereof, there being an opening in 35 each of said recesses, the inner wall and cup-shaped recesses forming a basket-like receptacle for the reception of a dust-containing-fabric therein, a dust collecting bag connected to a side of said housing and in communication with the 40 latter, and means for actuating said fan.

ALFRED J. ZUGEHOER.
